UNITED STATES PATENT OFFICE.

HENRY POHLMANN, OF NEW YORK, N. Y.

JOINING DEVICE.

No. 873,599.

Specification of Letters Patent.

Patented Dec. 10, 1907.

Application filed April 13, 1907. Serial No. 367,943.

To all whom it may concern:

Be it known that I, HENRY POHLMANN, a citizen of the United States, and a resident of the city of New York, borough of Manhattan, in the county and State of New York, have invented a new and Improved Joining Device, of which the following is a full, clear, and exact description.

The invention relates to wood-working, and its object is to provide a new and improved joining device for securely and firmly holding wooden parts together, such as the wrest plank and back frame of a piano, to provide for the strain exerted on the wrest plank by the strings.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a plan view of the improvement as applied; Fig. 2 is a sectional side elevation of the same, on the line 2—2 of Fig. 1, and Fig. 3 is a perspective view of the improvement.

As illustrated in Figs. 1 and 2, the wrest plank A of a piano is glued to the back frame B in the usual manner, and in order to prevent the wrest plank A from being torn loose by the strain exerted on the wrest plank by

the piano strings, a joining device is provided, preferably made of a single piece of metal, formed with a loop C, a shank D and a head E. The loop C has its lower edge C¹ sharpened, to permit of readily driving the

loop down into the top of the back frame B, in the direction of the grain of the wood, the wood being held against splitting by providing the top of the back frame B with transversely extending saw cuts B¹, as plainly

shown in Fig. 1, the saw cuts also permitting an easy driving of the loop C down into the wood. The shank D and the head E fit snugly into a recess formed across the top of the wrest plank A, the head E being pre-

ferably triangular in shape, the base of the triangle forming the outer face of the head, and the said face being flush with the front face of the wrest plank A, as shown in Figs. 1 and 2. The sides of the shank D are provided with vertically extending lugs D¹, hav-

ing their lower ends D² sharpened to readily pass into the wood of the wrest plank A when the device is driven into position, it being understood that the grain of the wrest plank runs in a longitudinal direction, that is, at right angles to the shank D but in alignment with the lugs D¹, for the latter to readily pass into the wood without danger of splitting the same. The lower portion of the shank D and its head E extend somewhat below the sharpened bottom edge C¹ of the loop C, to provide a greater depth for the shank D and the head E, thus increasing the holding capacity of the head E on the wrest plank A.

As shown in Figs. 1 and 2, the front portion of the wrest plank A is usually made of several layers of wood A¹ glued together, and by the use of the device all the parts which are glued together are securely held in place, and the wrest plank A is capable of readily withstanding the strain exerted by the strings on the string pins attached to the wrest plank A in the usual manner.

In practice, a number of joining devices, as shown and described, are used for each wrest plank, the several devices being spaced suitable distances apart, but each is flush with the top with the wrest plank A and the back frame B, and the face of the head E is flush with the front face of the wrest plank, so that no undesirable projections are produced.

Although I have shown the loop C of approximately egg-shape, I do not limit myself to this form, as the same may be varied, and also I do not limit myself to the particular shape given to the head E.

As the device is made of a single piece of metal, it can be cheaply manufactured and readily placed in position to securely hold the wooden parts together.

Having thus described my invention, I claim as new and desire to secure by Letters Patent:

1. A device for joining wooden parts comprising a loop for engagement with one of the wooden parts, a shank projecting integrally from the loop and engaging the other wooden part, and a head integrally on the end of the shank for engaging the face of the part engaged by the said shank.

2. A device for joining wooden parts comprising a loop for engagement with one of the wooden parts, a shank projecting inte-

grally from the loop and having lugs on the sides, the said shank and lugs engaging the other wooden part, and a head integrally on the end of the shank for engaging the face 5 of the part engaged by the said shank.

3. A device for joining wooden parts comprising a loop having its lower end beveled, for engagement with one of the wooden parts, a shank projecting integrally from 10 the loop and engaging the other wooden part, and a head integrally on the end of the shank for engaging the face of the part engaged by the said shank.

4. A device for joining wooden parts comprising a loop for engagement with one of the wooden parts, a shank projecting integrally from the loop and engaging the other wooden part, and a head integrally on the 15 end of the shank for engaging the face of the part engaged by the said shank, the said head being approximately triangular in shape, the base of the triangle forming the outer face of the head.

5. In combination, the wooden parts to 25 be joined together, and a joining device for the said wooden parts and formed of a single piece of material, having a loop, a shank and a head, of which the loop is driven into one of the wooden parts and the shank and 30 head fitting into corresponding recesses formed in the other wooden part.

6. In combination, the wooden parts to be joined together, and a joining device for the said wooden parts and formed of a single 35 piece of material, having a loop, a shank and a head, of which the loop is driven into one of the wooden parts and the shank and head fitting into corresponding recesses formed in the other wooden part, the wooden part

receiving the loop being provided with saw 40 cuts to permit ready entrance of the loop.

7. In combination, the wooden parts to be joined together, and a joining device for the said wooden parts and formed of a single piece of material, having a loop, a shank and 45 a head, of which the loop is driven into one of the wooden parts and the shank and head fit into corresponding recesses formed in the other wooden part and across the grain thereof.

8. In combination, the wooden parts to be joined together, and a joining device for the said wooden parts and formed of a single piece of material, having a loop, a shank and 50 a head, of which the loop is driven into one of the wooden parts and the shank and head fit into corresponding recesses formed in the other wooden part, the said shank being provided at its sides with vertical lugs pointed at the lower ends and adapted to be driven 55 into the wood.

9. A device for joining wooden parts comprising a loop for engagement with one of the wooden parts, a shank projecting integrally from the loop and engaging the other 65 wooden part, and a head integrally on the end of the shank for engaging the face of the part engaged by the said shank, the height of the shank and head exceeding that of the loop.

In testimony whereof I have signed my name to this specification in the presence of two subscribing witnesses.

HENRY POHLMANN.
